UNITED STATES PATENT OFFICE.

ZACARIAH T. STORY, OF CALHOUN, LOUISIANA, ASSIGNOR OF ONE-HALF
TO EDGAR O. LEWIS, OF CALHOUN, LOUISIANA.

RAILWAY CATTLE-GUARD.

Specification of Letters Patent.

Patented Dec. 25, 1906.

No. 839,225.

Application filed October 6, 1906. Serial No. 337,839.

To all whom it may concern:

Be it known that I, ZACARIAH T. STORY, a citizen of the United States, residing at Calhoun, in the parish of Ouachita and State of Louisiana, have invented a new and useful 5 Railway Cattle-Guard, of which the following is a specification:

This invention relates to railway cattle-guards.

10 The objects of the invention are to improve and simplify the construction of such devices; furthermore, to increase their efficiency in operation and to decrease the expense attending their instalment and main- 15 tenance.

With the foregoing and other objects in view, which will appear as the description proceeds, the invention resides in the combination and arrangement of parts and in the 20 details of construction hereinafter described and claimed; it being understood that changes in the precise embodiment of invention herein disclosed can be made within the scope of the following claims without departing from the spirit of the invention or sacrificing any of its advantages.

In the accompanying drawings, forming part of this specification, Figure 1 is a side elevation; partly in section, of a cattle-guard constructed in accordance with the invention; Fig. 2 is a transverse section; and Fig. 3 is a plan view.

Like reference characters indicate corresponding parts in the different figures of the drawings.

35 The reference-numeral 1 is used to indicate the steel rails, and 2 the ties of the road-bed.

In order to enable the improved cattle-guard of this invention to be installed at 40 small expense, it is proposed to employ a supporting-frame, which is indicated generally by A and is adapted to be easily and quickly secured in position between the rails 1, so as to support practically the entire weight of 45 the operating mechanism of the gate. The frame A preferably comprises the side bars 3, end bars 4, and legs or brackets 5, which are approximately Z-shaped and are securely fastened at their lower ends to the ties 2 and 50 at their upper ends to the side bars 3, as shown. It will be obvious that the supporting-frame A can be easily and quickly secured in position at any desired point upon a

railroad, it being only necessary to fasten the legs 5 upon the rail-ties, as set forth above. 55

It may be here explained that each cattle-guard constructed in accordance with this invention comprises a plurality of sets of guard-frames or gates which extend in opposite directions and which are adapted to be 60 operated by the weight of an animal to raise the same into operative position. As both sets of guard-frames or gates are similar in construction, a description of one will suffice to convey an understanding of both.

65 The reference-letter B indicates what I shall term a "main guard-frame or gate," which preferably consists of a plurality of sections 6, 7, and 8, one of said sections being located between the tracks and the other 70 two on opposite sides of the tracks, as shown. Each of the sections 6, 7, and 8 is connected with a main-frame shaft 9, which is mounted intermediate its ends within suitable journal-brackets 10 upon the supporting-frame 75 A, as shown. On opposite sides of the main frame A the shaft 9 is formed with crank portions 11, which extend downward beneath the rails 1 in such manner as to permit the necessary partial rotation of the shaft 9. 80 The opposite ends of the shaft 9, with which the outer sections 6 and 8 of the main guard-frame are connected, are free and unsupported except by the frame A. The auxiliary guard-frame C, which is adapted to be folded 85 against the tracks beneath the main guard-frame B, consists of a plurality of sections, one of which is located between the tracks and the other two on opposite sides thereof. Each of the sections of the auxiliary guard-frame C consists of an upper set of fingers 12 and a lower set 13, said lower set 13 diverging with respect to the upper set 12, as shown. The sets of diverging fingers 12 and 13 are suitably connected with an auxiliary frame-shaft 14, which is journaled in suitable 90 brackets 15 on the under side of the side bars 3 of the supporting-frame A, it being understood that the journal-brackets 10 of the main-frame shaft 9 are mounted upon the upper surface of said side bars, as shown. On opposite sides of the supporting-frame A the auxiliary-frame shaft 14 is formed with 95 crank portions 16, which extend under the rails 1, as shown.

100 The means for raising the main and aux-

iliary guard-frames into operative position upon the approach of an animal preferably consists of a plurality of movable platforms 17, one of which is disposed between the 5 tracks and the others on opposite sides thereof, so that each of said movable platforms will be arranged adjacent one of the pairs of main and auxiliary guard-frames. The platforms 17 are suitably mounted upon 10 a platform-shaft 18, which is mounted in journal-brackets 19, secured against the under surfaces of the side bars 3 of the supporting-frame A. The platform-shaft 18 is formed with crank portions 20, extending beneath the rails 1. The outer free ends of the platform-shaft 18 preferably are braced or upheld by means of supporting-arms 21, which serve to prevent the weight of the outer movable platforms 17 from bending or breaking 15 the shaft. Each of the platforms 17 preferably is provided with a pair of side bars 22, which extend toward the main and auxiliary guard-frames B and C, as shown, said side bars being connected with each other by a 20 cross-bar 23, which extends across the under side of the adjacent section of the main guard-frame B. The side bars 22 and cross-bar 23 of each movable platform 17 serve to produce a rectangular inclosure in which the 25 adjacent section of the auxiliary guard-frame C lies, the upper set of diverging fingers 12 being adapted when in lowered position to rest upon the platform-shaft 18, so as to limit the downward movement of the auxiliary guard-frame, it being understood that the lower diverging set of fingers 13 preferably are shorter than the upper set 12, so as to clear the platform-shaft 18 upon their 30 downward movement. The fingers of each 35 section of the main guard-frame B preferably extend over the cross-bar 23 of the adjacent movable platform 17 and are of sufficient length to overlap the platform-shaft 18 and to rest upon the platforms 17 in such manner 40 as to be limited in their downward movement, said fingers being preferably formed with bent ends 24, as shown, so as to avoid presenting any upward-projecting ends which might have a tendency to be caught by a 45 chain dragging from a passing train.

The connection between each of the movable platforms 17 and the adjacent guard-frames consists, preferably, of a link 25, which is pivotally connected at one end with the cross-bar 23 of the movable platform and is similarly connected at its opposite end with an arm 26, which depends rigidly from the adjacent portion of the main-frame shaft 50. The link 25 is pivotally connected with the depending arm 26, intermediate the ends thereof, as shown at 27.

Pivotally connected with the lower end of each depending arm 26 is a second link 28, which is pivotally connected at its opposite end with the lower end of a second depend-

ing arm 29, rigidly connected with the adjacent portion of the auxiliary-frame shaft 14, as shown.

It will be obvious that when an animal, such as a cow, depresses one of the platforms 17 the forward end of said platform carrying the cross-bar 23 will be raised, thus causing the link 25 to draw upon the depending arm 26 and also causing the second link 28 to operate the second depending arm 29, whereby the main guard-frame B will be raised into its highest operative position and the diverging sets of fingers 12 and 13 of the auxiliary guard-frame C will be disposed in intermediate planes, so as to present a phalanx of fingers to prevent the passage of the animal along the railroad-track. As soon as the animal moves away from the platform 17 the main and auxiliary guard-frames will drop by gravity into their lowered position.

It is one of the objects of the present invention to provide signal means for notifying the engineer of an approaching train that an animal has approached the cattle-guard and has raised the gates. The preferred means for notifying the engineer consists of a mast 30, which is provided at its upper end with a signal-arm 31. The arm 31 is adapted to be raised into horizontal position by means of a link-rod 32, connected at its lower end with a bell-crank lever 33. The bell-crank lever 33 in turn is connected, by means of a second link-rod 34, with a second bell-crank lever 35, which is adapted to be operated by means of a third link-rod 36, pivotally connected with one of the depending arms 29 of the auxiliary guard-frame, so that when the guard-frames are raised the signal-arm 31 will be operated, through the connections described, to notify the engineer of an approaching train that the road is obstructed.

The improved railway cattle-guard of this invention is strong, simple, durable, and inexpensive in construction, as well as thoroughly efficient in operation.

What is claimed is—

1. A railway cattle-guard having a main guard-frame, and an auxiliary guard-frame located beneath the main guard-frame and having a plurality of sets of diverging fingers.

2. A railway cattle-guard having a platform provided with side bars and a cross-bar forming an inclosure, an auxiliary guard-frame adapted to be raised through said inclosure, and a main guard-frame adapted to extend over said cross-bar and auxiliary guard-frame.

3. A railway cattle-guard having a platform provided with side bars and a cross-bar, a main guard-frame having a shaft provided with a depending arm, a link connecting the cross-bar of said platform with said depending arm intermediate the ends thereof, an auxiliary guard-frame having a depending arm, and a second link connecting the lower

end of the depending arm of the main guard-frame with the depending arm of the auxiliary guard-frame.

4. A railway cattle-guard having a supporting-frame adapted to be mounted between the rails, a platform-shaft journaled upon said supporting-frame and having crank portions located beneath the rails, platforms connected with said platform-shaft and each having side bars and a cross-bar forming an inclosure, an auxiliary-frame shaft journaled upon said supporting-frame and having a plurality of sets of diverging fingers located in the inclosure formed by the side and cross bars of the platform and adapted to be limited in their downward movement by the platform-shaft, a main guard-shaft pivotally mounted upon the upper surface of the supporting-frame, a main guard-frame connected with said main-frame shaft and consisting of a plurality of sets of fingers having bent ends adapted to rest upon the adjacent platform and be thereby limited in their downward movement, depending arms

connected with the main-frame shaft, links 25 connecting said depending arms with the cross-bars of the adjacent platforms, depending arms connected with said auxiliary-frame shaft, links connecting the depending arms of the main-frame shaft with the depending 30 arms of the auxiliary-frame shaft, and signal mechanism adapted to be operated simultaneously with said main and auxiliary frames.

5. A railway cattle-guard having a main guard-frame, an auxiliary guard-frame located adjacent thereto and having a plurality of sets of diverging fingers, means adapted to be operated by an animal for simultaneously raising the guard-frames, signal means, and mechanism for actuating the same simultaneously with the guard-frames.

In testimony that I claim the foregoing as my own I have hereto affixed my signature in the presence of two witnesses.
